UNITED STATES PATENT OFFICE.

HJALMAR G. CARLSON, OF WORCESTER, MASSACHUSETTS, ASSIGNOR, BY MESNE ASSIGNMENTS, TO ROCKWOOD SPRINKLER COMPANY OF MASSACHUSETTS, OF WORCESTER, MASSACHUSETTS, A CORPORATION OF MASSACHUSETTS.

UPSETTING TOOL.

1,402,919.

Specification of Letters Patent. Patented Jan. 10, 1922.

Application filed September 21, 1918. Serial No. 255,174.

To all whom it may concern:

Be it known that I, HJALMAR G. CARLSON, a citizen of the United States, residing at Worcester, in the county of Worcester and 5 State of Massachusetts, have invented a new and useful Upsetting Tool, of which the following is a specification.

This invention relates to a set of dies for upsetting purposes.

10 The principal object of the invention is to provide a construction of die which will permit of the upsetting of a blank or unfinished article in such a way as to form a square shoulder, and also in the preferred 15 form of the invention to produce a thick transverse wall or diaphragm terminating in said shoulder. Another object is to produce these results by operations that involve no 20 waste of metal because none of it has to be removed from the article. Further objects and advantages of the invention will appear hereinafter.

Reference is to be had to the accompanying drawings, in which—

25 Fig. 1 is a central sectional view of material portions of a die press showing a preferred embodiment of this invention applied thereto;

30 Fig. 2 is a similar view on enlarged scale showing merely the die cavity and associated parts, and

Fig. 3 is a similar view showing the parts in the position they assume when the upsetting operation is completed.

35 The invention is illustrated herein as used for the purpose of performing one operation in the manufacture of a combined adapter and booster casing A. This is received in the machine in the form shown in Figs. 1 and 40 2 in which it has a small cylindrical closed end, a large cylindrical open end a and a flat flange. The operation of the machine reshapes and shortens its large end to the form shown in Fig. 3 in which the sloping shoulder is squared up and a thick diaphragm or transverse wall a' is formed. It 45 is to be understood, however, that the invention is capable of use in connection with the manufacture of other articles of a similar shape, and in fact of various other shapes. While this is an upsetting operation 50 it is performed by means of a die and punch so arranged that when the punch comes to its seat against the metal in the die, it will

force the metal out into the form of a sharp 55 shoulder and at the same time thicken the metal transversely so as to make a thick transverse wall or diaphragm.

Enough of the press is shown to illustrate the metal working operation, which is the 60 subject of this invention. For that purpose I have shown the press bolster plate 10 supporting the usual die bed 11. This die bed supports a female die shown as consisting of a plurality of members. For mechanical 65 reasons I prefer to make it in several pieces. There is a central member 12 for receiving the blank A and the headed ejector 13 at the bottom. It supports a second member 14 which is hollowed out at the center to 70 receive central die member 15. On this die member 15 is supported a shoulder-forming die member 16 in the form of a ring having a flange at the bottom resting on the member 15. This member 16 is held firmly in 75 position against the member 15 by a plate 17 held down by screws 18 entering the die bed. The member 14 is provided with sockets which support springs 20 which in turn support a movable die plate 21 adapted to 80 move back and forth between the inner surface of the recess in the member 17 in which it is located and a stop plate 22 in the form of a ring. This is held down by the screws 85 18 and it projects over the edge of the plate 21. The springs 20 normally hold this plate 21 up against the plate 22.

Also supported by the bolster plate are a pair of bolts 25 provided with springs 26, which springs hold up a stripper or pressure 90 plate 27 which is movable up and down guided by the bolts 25. This plate is provided with a central platen 28 which, as will be seen, forms a part of the shaping mechanism. The parts 27 and 28 are positively 95 and firmly forced down by the bottom of the press slide 29 by well-known means as indicated. These parts 27 and 28 therefore, reciprocate with the press slide 29 positively.

100 In the press slide 29 is a recess at 30 having a strong spring 31 therein pressing on a movable member 32 which supports a block 33 which presses down on the head of the plunger 34. This plunger projects through 105 the platen 28 and is centrally located with respect to the cavities in the stationary parts of the die below, as is well understood in this

art. Above the member 32 is a block 35 which rests loosely thereon and is spaced slightly from the top of the recess 30. In the operation of the plunger 34, due to the 5 reciprocation of the slide 29, the plunger is normally under the pressure of the heavy spring 31 at all times. If, however, any obstacle is met that increases the difficulty of forcing the plunger into the dies or article 10 below, the amount that it can yield is limited by the length of the space between the top of the block 35 and the top of the recess 30. The plunger is shown as longitudinally perforated to let the air out of the blank A 15 when it descends.

The operation of the device is as follows: The partly finished article or blank A of cold drawn sheet metal is put into the central recess or cavity in the die plate 21 by hand. 20 It will normally slide down either into the position shown in Figs. 1 and 2 or nearly to that position. The press is then operated to bring the plunger down under the pressure of the spring 31 and the platen 28 down positively. 25 Before the plunger encounters any great resistance the platen 28 encounters and presses down upon the flat flange of the article A, which rests on the top of the die plate 21. As this platen 28 continues to descend 30 under the influence of the positive pressure of the slide, it lowers the plate 21 against the resistance of the springs 20, and during that period the plunger continues to descend until it reaches the bottom of the article. 35 The plunger is provided with a shoulder at 36 which comes finally into the position shown in Fig. 3.

It will be noted that the ring 16 is stationary and cannot descend with the plate 21, 40 but the open end of the article A with its flat flange does descend under the positive pressure of the platen 28. Therefore the metal in the portion *a* of the blank is upset and forced out into the shoulder formed between 45 the outer edge of the ring 16 and the central passage through the die plate 21, as well as into the upper shoulder on the inside edge of the flange and against the shoulder 36 on the plunger. These parts are so proportioned 50 and arranged that the diaphragm or transverse wall *a'* of the article being operated upon is materially thickened because it receives some of the surplus metal from the portion *a*.

55 When the plunger 34 and platen 28 are withdrawn the springs 20 tend to force the die plate 21 up to the original position and thus loosen the article from the dies below, and then the ejector 13 is operated in the 60 usual way to force it out. It is to be observed that the plunger 34 both in its small and large sections is made to fit exactly in the blank as it is originally put into the press. Except for the shoulder 36, it is just 65 like the plunger previously used to bring

the blank up to that shape. So its only effect is to hold the metal and prevent its being squeezed inwardly in any direction except to fill out the shoulders as above mentioned. The positive compression due to the 70 lowering of the platen 28 on the external flange of the article is also essential for the same purpose. This has to press down firmly on the article in order to avoid any danger of the flange itself receiving any of the 75 surplus metal from the section *a*.

It will be understood, of course, that while I have described the invention as employed in the production of a particular article and the formation of a shoulder and thickened 80 wall at a certain point therein, the invention is not limited to the production of an article of that shape or even to articles of similar shapes, but is of a general character as represented in the claims.

85 Therefore I do not wish to be limited to all the details of construction herein shown and described, but what I do claim is:—

1. The combination of a die comprising a part for receiving and holding the article or blank to be operated upon and a relatively movable plate beyond the first named part and normally spaced from it but having only a limited range of motion relative thereto, and a second die member relatively movable 95 to engage the article in the first die and provided with means associated with it for engaging said relatively movable plate so as to hold any part of the article extending between them, and then by their relative motion upset the metal.

2. In a machine for upsetting a blank having a tubular part provided with a larger diameter at one place than at another and a shoulder at the end of the larger part, the 105 combination of a die for supporting said blank provided with a member surrounding the blank and adapted to abut against the shoulder thereof, a yieldingly mounted plate having a passage therethrough for the surrounding member and for receiving the large tubular portion of the blank, and means whereby pressure can be exerted against said movable plate and at the same time hold the edge of the blank and force its 110 larger part longitudinally to upset the metal 115 against the edge of said surrounding member and shape the shoulder.

3. In a device of the character described, the combination of a pair of dies, one die 120 having a cavity for receiving a substantially tubular article to be shaped therein and having a stationary part fitting the article and also a relatively movable yielding plate having a passage through the center thereof for said stationary part, whereby when moved longitudinally toward the stationary part the distance between the end of the stationary part and the corresponding end of the movable plate will be reduced, and a 125 130

second die comprising a plunger adapted to project into said cavity and a stripper and pressure platen surrounding the plunger and adapted to engage the yielding or movable plate to force it longitudinally.

4. The combination of a die bed, a female die thereon having a fixed part and a movable plate, the movable plate having only a limited range of movement, springs for holding the movable plate in one extreme position, a plunger movable into and through said die, and a pressure platen movable with the plunger for engaging any part of the article or blank to be shaped which projects beyond said movable plate and forcing the same longitudinally with said movable plate, whereby part of the metal in the blank will be upset and forced into any depressions in the die.

5. In a machine for upsetting a blank having a tubular part provided with a larger diameter at its open end than at the closed end and a flange on its open end, the combination of a stationary die for supporting said blank, said die comprising a ring-shaped member at the end thereof for receiving the end of the smaller portion of the tubular blank, the end of said ring abutting against the shoulder of the blank at the end of said larger portion, a yieldingly mounted plate having a passage therethrough fitting the ring-shaped member and the large tubular portion of the blank, means for limiting the motion of the plate, means for pressing on the flange on said yielding plate and at the same time holding the edge of the blank and forcing it longitudinally with the yielding plate to upset it against the end of said ring shaped member, and a plunger fitting the interior of the blank and movable with said means to prevent any flow of the metal inwardly while the large portion of the blank is being upset.

6. In a machine for upsetting a blank having a tubular part provided with a larger diameter at its open end than at the closed end, the combination of a stationary

die for supporting said blank, said die comprising a ring-shaped member for receiving the end of the smaller portion of the tubular blank, the end of said ring abutting against the shoulder of the blank at the end of said larger portion, a yieldingly mounted plate having a passage fitting the ring-shaped member and the large tubular portion of the blank, means for pressing on said yielding plate and at the same time holding the edge of the blank and forcing it longitudinally with the yielding plate to upset it against the end of said ring-shaped member, and a plunger fitting the interior of the blank to prevent any flow of the metal inwardly while the large portion of the blank is being upset.

7. The combination of a die bed, a female die thereon having a fixed part and a movable plate, the movable plate having only a limited range of movement, springs for holding the movable plate in one extreme position, a plunger movable into and through said die, a pressure plate movable with the plunger for engaging any part of the article or blank to be shaped which projects beyond said movable plate and forcing the same longitudinally with said movable plate, positive means for moving said pressure plate into position to hold the article and move it and the movable plate, and yielding means for moving the plunger with the pressure plate.

8. The method of upsetting a tubular blank which consists in positively holding the interior of the blank at all points to prevent flow inwardly, also holding its exterior at both ends thereof and positively gripping the open edge, confining the portion of the blank beyond the point at which it is held on the exterior and then moving the open end of said blank longitudinally to upset the metal and fill all interstices in the holding means.

In testimony whereof I have hereunto affixed my signature.

HJALMAR G. CARLSON.
